CLAIM

I claim the ornamental design for a furniture with drawers, as shown and described.

DESCRIPTION

FIG. 1 is a perspective view of the furniture with drawers in accordance with the present invention;

FIG. 2 is a front elevation view of the furniture with drawers of FIG. 1;

FIG. 3 is a first side elevation view of the furniture with drawers of FIG. 1;

FIG. 4 is a top plan view of the furniture with drawers of FIG. 1;

FIG. 5 is a rear elevation view of the furniture with drawers of FIG. 1;

FIG. 6 is a second side elevation view of the furniture with drawers of FIG. 1; and,

FIG. 7 is a bottom plan view of the furniture with drawers of FIG. 1.

(Continued)

The broken lines shown in the drawings are for the purpose of illustrating portions of the article and form no part of the claimed design.

1 Claim, 3 Drawing Sheets
